(57) **CLAIM**

What is claimed is the ornamental design for a eye shield, as shown and described.

DESCRIPTION

FIG. 1 is a front perspective view of an eye shield, showing the new design;

FIG. 2 is a front elevational view thereof;

FIG. 3 is a rear elevational view thereof;

FIG. 4 is a right side view thereof, the left side view being a mirror image thereof;

FIG. 5 is a top plan view thereof;

FIG. 6 is bottom plan view thereof; and,

FIG. 7 is a rear perspective view thereof.

The broken line showing of a person in FIG. 1 are included for the purpose of illustrating environmental structure and forms no part of the claimed design.
